UNITED STATES PATENT OFFICE.

CHARLES W. E. CLARKE, OF NEW YORK, N. Y.

MANUFACTURE OF AIR-HEATING ELEMENTS.

Original application filed March 11, 1924, Serial No. 698,405. Divided and this application filed November 15, 1924. Serial No. 750,079.

My invention relates to the manufacture of air heating elements, and has special reference to blanks for heating elements and to a method of constructing and assembling the blanks. A heating element of the type to which the invention relates particularly comprises two plates of sheet metal arranged side by side and spaced apart with their edges welded together, means being provided for directing air to be heated through the space between the plates.

An object of the invention is to provide blanks of novel and improved construction for air heating elements of this character.

Another object of the invention is to provide a novel and improved method of forming the blanks.

Another object of the invention is to provide a novel and improved method of constructing a heating element of the character indicated.

The several features of the invention, whereby the above mentioned and other objects may be attained, will be clearly understood from the following description and accompanying drawings, in which:

Figure 1 is a front elevation partly in section, of an air heating apparatus embodying air heating elements constructed in accordance with my invention, the apparatus being shown inserted in the uptake flue of a furnace;

Fig. 2 is a detail side elevation of one of the air heating elements;

Fig. 3 is a sectional view, on an enlarged scale, taken on the line 3—3 of Fig. 2;

Figs. 4 and 5 are detail sectional views taken on the lines 4—4 and 5—5, respectively, of Fig. 2;

Figs. 6 and 7 are detail views in perspective of component parts of the air heating element;

Fig. 8 is a view similar to Fig. 2 of a modified construction of heating element;

Fig. 9 is a sectional view taken on the line 9—9 of Fig. 8, showing a plurality of the heating elements assembled;

Figs. 10 and 11 are sectional views on an enlarged scale taken on the lines 10—10 and 11—11 of Fig. 14;

Figs. 12 and 13 are detail views in perspective of component parts of the heating element illustrated in Fig. 8;

Fig. 14 is a view in perspective of one of the plates of the heating element illustrated in Fig. 2; and

Fig. 15 is a similar view of one of the plates of the heating element illustrated in Fig. 8.

The air heating apparatus illustrated in Fig. 1 of the drawings is of the type of the one described and claimed in my pending application Serial No. 698,405, filed March 11, 1924, of which the present application is a division. As shown, the air heating apparatus is provided with a casing which is arranged vertically and has its lower end connected with a header 2 which may lead from the flue gas outlet of a boiler furnace, and has its upper end connected with a header 4

which may lead to the furnace chimney. This casing is provided with front and rear walls 6 and 8, respectively, and with side walls 10. The casing is divided by partitions 12 into two air heating sections 14 and 16 having a gas by-pass 18 between them which is adapted to be opened and closed by means of a damper 20. Each of the side walls 10 of the casing is provided with an air inlet opening 22 which may be open to the atmosphere or may be connected by a conduit 24 with a source of air supply, and is further provided with an air outlet opening 26 which may be suitably connected by a conduit 28 with the wind box of the furnace.

Each of the air heating sections 14 and 16 contains a plurality of air heating elements 30 arranged vertically side by side and spaced apart and extending between the side wall 10 of the heating section and the partition or wall 12. Each air heating element comprises two plates 32 and 34 (Figs. 2 and 3) that are arranged side by side and spaced apart. Each of the elements is provided with an air inlet opening 36 and an

air outlet opening 38, the air inlet and outlet openings of the several elements in each heating section being in communication with the air inlet and outlet openings 22 and 26, respectively, of the section. Each air heating element is divided into a plurality of passages extending between the inlet and outlet openings thereof by means of

suitably arranged angle irons 40 secured to one of the plates. The several heating elements of each heating section are held spaced apart to provide gas passes between them by means of vertically arranged angle irons 42 that are welded or otherwise secured to one of the plates of each heating element.

The modified construction of air heating

element illustrated in Figs. 8 and 9 comprises two plates 32' and 34' that like plates 32 and 34 are arranged side by side and spaced apart. This element also is provided with inlet and outlet openings 36' and 38', angle irons 40' secured on the inside side of one of the plates, and angle irons 42' secured on the outside of the plate 32', which parts may be the same as the corresponding parts of the air heating element first described.

The parts above referred to may be and preferably are the same as the corresponding parts of the air heating apparatus illustrated and described in my pending application hereinbefore referred to, to which reference may be had for a full and complete description of the same.

In accordance with the present invention, in constructing each plate of the air heating element illustrated in Fig. 2, a substantially flat sheet is provided which is cut to form a substantially rectangular body portion, Fig. 14, having one of its longitudinal edges provided with two projecting marginal portions adjacent the ends thereof forming flanges 44, the upper projecting portion or flange having its upper end spaced a slight distance from the upper edge of the body of the plate, the lower projecting portion or flange having its lower end spaced a slight distance from the lower edge of the body portion, and the inner ends of said projecting portions or flanges being spaced a distance apart. The inner longitudinal portion of each of said portions or flanges 44 are bent to form the inclined portion 46, and the outer portion 48 which is arranged parallel with the body of the plate. The ends of the central marginal portion 50 between the inner ends of said flanges 44 are slitted at 52, and this central marginal portion is bent in the opposite direction to the inclined portions 46 of the flanges 44. The opposite corners of the plate at the ends of the other longitudinal edge are provided with diagonal slits 54, and the marginal portion of this longitudinal edge and the marginal portions of the ends of the body of the plate are bent in the same direction as said central marginal portion 50. The slits 54 are of suitable shape so that when the marginal portions of the latter longitudinal edge and the ends of the plate are bent, the edges of the adjacent ends thereof are brought together. These edges are then welded, which completes the formation of the plate.

The two plates 32' and 34' are assembled to form the heating element after the angle irons 40' have been applied to one of them as hereinbefore described, by bringing the plates together with the edges of the inwardly bent

marginal portions of the plates positioned in engagement, and then welding these edges together.

The upper flanges 44 of each air heating element forms the air inlet opening 36 thereof, and the lower flanges 44 the air outlet opening 38. The spaces at the upper and lower outer corners of each heating element formed by the outwardly turned flanges 44 are closed by castings 56 of suitable shape to permit them to be inserted between the plates, and the spaces between the inner ends of the flanges 44 of each pair are closed by suitably shaped castings 58. The castings 56 and 58 are welded to the plates so as to form air tight joints.

The plate 32' of the modified construction of heating element illustrated in Figs. 8 and 9 is flat throughout its area and the body portion thereof is substantially rectangular. One of the longitudinal edges of the body portion of this plate 32' is provided with two projecting marginal portions or flanges 60, the upper end of the upper flange being spaced a slight distance from the upper end of the plate and the lower end of the lower flange being spaced a slight distance from the lower end of the plate. The plate 34' corresponds substantially in contour to the plate 32'. The flanges 44' of the plate 34', which correspond to the flanges 60 of the plate 32' are bent outwardly as shown to provide an outwardly inclined portion 46' and a portion 48' in a plane parallel to the plane of the body of the plate. The margins of the portion 50' of the plate 34' between the flanges 44', the end margins of the plate, and the margin of the other longitudinal edge of the plate are bent inwardly at an angle. The opposite corners of the plate 34' at the ends of the other longitudinal edge are provided with diagonal slits 54', and the marginal portions of the ends of the body of the plate are bent in the same direction as said central marginal portion, the slits 54' being of suitable shape so that when the marginal portions of the latter longitudinal edge and the ends of the plate are bent, the edges of adjacent ends thereof are brought together. These end edges are then welded which completes the formation of the plate.

The two plates 32' and 34' are assembled to form the heating element after the angle irons 40' have been applied to one of them as hereinbefore described, by bringing the plates together with the edges of the inwardly bent marginal portions of the plate 34' positioned in engagement with the corresponding edge portions of the plate 32', and then welding these engaging edge portions of the two plates together. The openings at the upper and lower outer corners formed by the flanges 60 and 44' are closed by castings 56' of suitable shape to permit

them to be inserted between the plates, and the spaces between the inner ends of said flanges of each pair are closed by suitable shape castings 58'. The castings 56' and 58' are welded to the plates so as to form air tight joints. It may be noted that the plate 34' is constructed in the same manner as each of the plates of the air heating first described except that in the former the bent 10 marginal portions and also the flanges 44' are wider than the corresponding parts of the latter plates.

As will be evident to those skilled in the art, my invention permits various modifications without departing from the spirit thereof or the scope of the appended claims.

What I claim is:

1. A blank for an air heating element of the class described comprising a substantially rectangular flat plate having marginal portions of its ends, one of its longitudinal edges, and the central portions of its other longitudinal edge bent in one direction from the body of the plate, and the marginal portions 20 of the last mentioned longitudinal edge between the ends of said central marginal portion and the ends of the body of the plate bent in the opposite direction.

2. A blank for an air heating element of the class described comprising a plate having a substantially flat rectangular body portion having one of its longitudinal edges provided with projecting flanges adjacent the ends of the plate, each of said flanges being 30 bent so that its inner longitudinal portion is transversely inclined in one direction to the body of the plate and its outer longitudinal portion is arranged substantially parallel with the body of the plate, and having 35 the marginal portions of the other longitudinal edge and the ends of the plate bent transversely in the opposite direction.

3. A blank for an air heating element of the class described comprising a substantially rectangular flat plate having marginal portions of its ends, one of its longitudinal edges and the central portion of its other longitudinal edge bent in one direction from the body of the plate, and having diagonally 45 extending slits in the corners of the plate at the ends of said longitudinal edge to enable the edges of adjacent ends of said marginal portions at said corners to be brought together, the portions of the other longitudinal edge of the plate between the ends of said 50 central portion and the ends of the plate being bent in the opposite direction.

4. A blank for an air heating element of the class described comprising a substantially rectangular flat plate having marginal portions of its ends, one of its longitudinal edges and the central portion of its other

longitudinal edge bent in one direction from the body of the plate, and having diagonally extending slits in the corners of the plate at 55 the ends of said longitudinal edge to enable the edges of adjacent ends of said marginal portions at said corners to be brought together, said edges being welded, and the portions of the other longitudinal edge of 60 the plate between the ends of said central portion and the ends of the plate being bent in the opposite direction.

5. The method of forming a blank for an air heating element of the class described 75 which comprises cutting a metal sheet so as to form a substantially rectangular plate, bending in one direction the marginal portions of its ends, one of its longitudinal edges, and the central portion of its other longitudinal edge, and bending in the opposite direction the marginal portions of the second mentioned longitudinal edge between 80 said central portion and the ends of the plate.

6. The method of forming a blank for an air heating element of the class described which comprises cutting a substantially rectangular plate from a flat sheet of metal, diagonally slitting opposite corners of the 90 plate at the ends of one of the longitudinal edges thereof, bending in one direction the marginal portions of said longitudinal edge and the marginal portions of the ends of the plate so as to bring adjacent ends of said 95 longitudinal and said end marginal portions together, welding said adjacent ends, bending in the same direction the central portion of the other longitudinal edge of the plate, and bending in the opposite direction the 100 marginal portions of said second mentioned longitudinal edge of the plate between the ends of said central portion and the ends of the plate.

7. The method of constructing an air heating element of the class described which comprises cutting a sheet of metal so as to form a substantially rectangular flat plate, bending in one direction the marginal portions of one of the longitudinal edges, the 105 ends, and the central portion of the other longitudinal edge of the plate, and bending in the opposite directions the marginal portions of the second mentioned longitudinal edge of the plate between said central portion and the ends of the plate, forming a second plate of substantially the size and contour of said first mentioned plate, applying it so as to bring the edges thereof 110 into engagement with the edges of said first mentioned bent marginal portions, and welding 115 said engaging edges together.

CHARLES W. E. CLARKE.
